ABSTRACT

A hopping game apparatus for children having a longitudinal semiflexible tubular bar supported at each end by a pair of semiflexible legs with each leg having a formed foot designed to prevent the lower ends of the legs from jamming into the ground, the legs being of equal length such as to maintain the longitudinal bar horizontal. Extending laterally from each side of the longitudinal bar are a plurality of pairs of semiflexible rods that are horizontal and at right angles to the longitudinal bar. The pairs of rods are equally longitudinally spaced from each other along the length of the longitudinal bar to provide between opposed rods on each side of the longitudinal bar hopping zones, or stations, for a child, the purpose of the game apparatus being to provide and/or permit a child to hop, high-step, skip, jump, leap or twist in midair to an about face turn from one zone or station to another, from one end of the apparatus to the other, or from side to side, or along one side and back on the other side. In accordance with rules established for the game there is provided a plurality of multicolored rings that a child can move from one rod to another rod when it successfully accomplishes the desired or selected action in moving from one zone or station to another.

A HOPPING GAME APPARATUS

This invention relates to a ground-supported game apparatus and has for its primary object a game device somewhat of the nature of a hopscotch court, the instant form of apparatus being a three-dimensional game having height requiring the player to move bodily vertically as well as either forward or backward in contradistinction to the conventional hopscotch court which is two-dimensional in which the player advances a marker as he moves along numbered squares without touching lines.

Another object of this invention relates to the provision of an apparatus of this character which is especially useful although by no means necessary, for children of various ages which is particularly adaptable in developing coordination, the ability to discern left from right, self-organization of a neuromuscular act in order to perform skilled movements and which in addition will also provide healthful body-building exercise particularly for the ankle and leg muscles.

Yet another object of this invention is to provide an apparatus of this character formed of a longitudinal bar, horizontally supported by a pair of legs at each end, the longitudinal bar having along the length thereof pairs of aligned horizontal transverse rods at right angles to the longitudinal bar, providing elevated zones or stations between opposed rods at each side of the longitudinal bar.

A further object of this invention is to form the longitudinal bar, legs and rods of a semiflexible material so as to give when struck by a player.

Another object of this invention is to have the legs inclined downwardly and outwardly from the ends of the longitudinal bar with each leg formed at its lower end with a lateral foot such as to obviate the leg from penetrating into the ground when the bar, rod or leg is accidentally struck by a player, the legs having a spreading action when the bar is struck or pushed down towards the ground.

Still another object of this invention includes the use of rings that may be multicolored that are moved by a player from one rod to another rod on completion of a successful hop or other physical action from one zone or station to another, it being contemplated that the game apparatus will be used by a number of players who will each use a ring of a selected color.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described within the the scope of the appended claims.

FIG. 1 is a perspective view of the game apparatus showing the rings used by the players on one of the rods thereof.

FIG. 2 is an end-elevational view of the game apparatus.

Referring to the drawings in greater detail the hopping game apparatus 10 is seen to consist of a central longitudinal tubular bar 12 preferably a polyethylene tube of at least 1 1/4-inch diameter and 60 inches in length, though obviously the dimensions may vary to suit requirements dictated by size, use and manufacture. While the central longitudinal tubular bar 12 is of polyethylene which has the desirable characteristics of semiflexibility, strength and lightness in weight it is to be understood that the same may be made of any other suitable material.

At each end of the tubular bar 12 there is provided legs 14, 15, 16 and 17. Legs 14, 15 comprise a pair at one end of the tubular bar 12 and legs 16, 17 comprise a pair at the other end of the tubular bar. The legs 14, 15, 16 and 17 may be of any desired semiflexible material but preferably are made of nylon rod at least three-eighth inch in diameter, and tapering slightly towards their bottom terminal end. Each leg at its upper end is threaded as at 19 for a portion of its length and carries at its lower end of the threaded portion 19 a clamping nut 20 of the "speed-nut" type. A dual pair of aligned openings are provided in the tubular bar 12 in longitudinally spaced relation, see FIG. 1, and each pair of openings is disposed at substan-

tially 45° to the vertical plane at the axis of the tubular bar 12, see FIG. 2. Fitted in each pair of aligned inclined openings is the threaded upper end of a leg which is recured to the tubular bar 12 by its clamp nut 20 and an end push-on cap 22. This construction makes for ease of assembly and disassembly. The lower end portions of the legs 14, 15, 16, 17 are each curved outwardly to provide a ground-engaging foot 24 that is slightly arcuate as seen in FIGS. 1 and 2. The curved formation of the feet 24 will prevent the legs from penetrating into the ground should a striking force by a player engage the tubular bar 12. Due to the semiflexible nature of the nylon legs 14, 15, 16, 17 and the slightly tapered formation thereof it will be seen that the legs of each pair will spread apart outwardly on impact on the tubular bar and that the feet 24 thereof will move or slide laterally outwardly in a direction away from the tubular bar.

The legs 14, 15, 16 and 17 are of equal length and the feet 24 thereof are similarly formed such that the tubular bar 12 will be supported in a horizontal position above the ground; the legs being so dimensioned and positioned as to support the tubular bar 12 at approximately 8 inches above the ground level.

Suitably positioned in spaced longitudinal relation along the longitudinal tubular bar 12 are a plurality of pairs of rods 30, 31; 32, 33; 34, 35 and 36, 37. Each pair of rods, may in fact, constitute a single unitary rod formed preferably of fiberglass tapering from its center portion which is preferably of at least 5/32-inch diameter towards its ends. The center portion The center portion of each rod is of uniform diameter and is functionally fitted or otherwise suitably secured in aligned horizontal openings in the longitudinal tubular bar 12, see FIG. 2, so that the rod sections 30, 31; 32, 33; 34, 35 and 36, 37 making up each pair of rods are horizontal and in the same plane and of equal length, as seen in FIGS. 1 and 2.

Preferably the end most rods 30, 31 and 36, 37 are respectively disposed between the connections of legs 14, 15, and 16, 17, as seen in FIG. 1 and the aligned pairs of rods are equally spaced apart approximately 20 inches to provide three zones or stations A, A'; B, B'; and C, C' at each side of the longitudinal tubular bar 12.

The above-described game apparatus which may be called "Hopsie" may be used by four to six players this being practical in consideration of waiting time. It is considered that the players will be children and in the use of the above apparatus there is provided a ring 40 for each child player. Each ring 40 which may be of plastic is of a different color so as to identify each player.

The playing of the game involves hopping, high-stepping, skipping, jumping (to both feet), leaping (to one foot), twisting in midair to an about-face turn, and combinations of these movement skills in series, while progressing over the rods from zone or station, as for example from A to B to C; or from A to A', to B' to B, to C to C'; or from A to B' to C and back again to C' to B to A', these movements from station to station requiring that the player not touch the rods or the tubular bar. As the player moves from station to station regardless of the nature of his bodily movement he will indicate his successful achievement of reaching a station by placing his ring on the rod in the path of his movement. Thus if he hops into station A successfully he will place his ring on rod 33. In other words using child play language in playing the game "one-sie"; "two-sie," etc., the player would place his ring over the first rod 31. If "one-sie" is completed by entering station A without touching any part of the apparatus the player removes the ring from rod 31 and hangs it over the "two-sie" rod 33 (next in line)—and so on.

It is seen that the object of the game is to perform the various bodily movement skills in an order as may be prescribed in an established "rules of the game" while avoiding touching of any parts of the apparatus as well as the rings which may be hanging at various stations indicating the progress made by the players. A "touching" or misstep indicates the end of the player's turn with a penalty of no advance.

Some suggested skill movements in the playing of the game are as follows:

ONE-SIE—"Hi-Step," over each rod; "Skip" over each rod on return.

TWO-SIE—"Straddle-jump" into first and second squares; jump-twist twice in the second squares; continue; repeat on return.

THREE-SIE—"Waltz," three-step in each square, traversing down; repeat on return.

FOUR-SIE—"Winding path," cross-step the central tube, skip-hop on each foot; repeat on return.

FIVE-SIE—"Around the World," lead laterally with near 10 foot, travel down one side and return on the opposite side.

SIX-SIE—"Bunny-Hop," jump both feet into each square, traverse across tube and forward; repeat on return.

SEVEN-SIE—"Pogo-Stick," leap to second square on outside 15 foot, step across tube, hop back one with inside foot, etc.,

EIGHT-SIE—"Whirligig," straddle-jump to second squares,

jump-twist, return to first squares, twist, repeat etc., NINE-

SIE—"Angel walks," place ring on head as 'halo,' rock-step laterally, one foot in left odd squares only, the other foot in right squares only, travel down length, and repeat on return. 'Halo' must not fall.

I claim:

1. A hopping apparatus comprising:

- a. a longitudinal bar,
- b. a pair of diverging legs removably secured to each end of the longitudinal bar supporting the same in a horizontal position above a supporting surface,
- c. a pair of transversely aligned flexible rods extending laterally from said longitudinal bar in substantially uniformly spaced relation therealong,

whereby

to provide a series of juxtaposed play stations for a player at each side of the longitudinal bar,

wherein:

- d. said longitudinal bar is semiflexible and formed of a non-metallic material,
- e. said legs being formed of a semiflexible nonmetallic material, and
- f. each said leg terminating at its lower end in a laterally outwardly directed arcuate foot,

whereby

said longitudinal bar and said flexible rods under impact will impart a spreading action to said legs to cause the feet thereof to move along the supporting surface.

2. A hopping apparatus comprising:

- a. a longitudinal bar,
- b. a pair of diverging legs removably secured to each end of the longitudinal bar supporting the same in a horizontal position above a supporting surface,
- c. a pair of transversely aligned flexible rods extending laterally from said longitudinal bar in substantially uniformly relation therealong,

whereby

to provide a series of juxtaposed play stations for a player at each side of the longitudinal bar,

wherein:

- d. said longitudinal bar is formed of a semiflexible tube of plastic material,
- e. said legs being formed of a semiflexible plastic material,
- f. said rods being formed of a flexible material,

wherein:

- g. the plastic material of the longitudinal bar is polyethylene,
- h. the plastic material of said legs is nylon, and
- i. the flexible material of said rods is fiberglass,

wherein:

- j. there being a dual pair of oppositely inclined aligned openings at each end portion of the longitudinal tubular bar with one pair of inclined openings of each dual pair in longitudinally spaced relation to the other pair of oppositely inclined openings,
- k. the inclination of said aligned pairs of openings being substantially 45° to a vertical plane through the longitudinal axis of the tubular bar,

- l. each leg at its upper end extending through a pair of said aligned inclined openings including fastener elements thereon for removably securing each leg to said tubular bar,

wherein:

said fastener elements for each leg comprises:

- m. a lower clamp nut threaded on the upper end portion of each leg engaging one side of the tubular bar,
- n. a push on cap fitted on the terminal end of each leg engaging the opposite side of the tubular bar,

wherein:

- o. each said leg tapers downwardly to its lower end, and
- p. an arcuate foot formed at the lower end of each leg directed laterally outwardly with reference to said tubular bar, and

whereby

said tubular bar under impact will cause legs to spread apart outwardly with their foot portions sliding over the supporting surface.

- c. the tapering rod sections of each unitary rod extending horizontally and laterally outwardly from the tubular bar,

3. The hopping game apparatus of claim 2, wherein said pairs of aligned laterally extending rods constitute:

- (a) a single unitary rod for each pair having a central portion of uniform diameter and tapering outwardly towards each terminal end thereof,

- (b) there being horizontally aligned pairs of openings in the tubular bar each pair fixedly receiving therein the central portion of a unitary rod,

- d. said tapering rod sections being of equal length and lying in the same horizontal plane.

4. The hopping game apparatus of claim 3 wherein:

- a. the central portion of the end most unitary rod at each end of the tubular bar providing an end pair of rod sections is positioned between the dual pair of aligned inclined openings within which the upper ends of the end pair of legs are fitted and secured.

5. The hopping game apparatus of claim 4, including:

- a. a plurality of different colored ring members,

- b. each ring member of a designated color identifying a player, and

- c. said rod sections receiving a ring member of a player either before or after a bodily movement action of a player to identify and signal the success of the bodily movement of the player from one play station to another as defined by said rod sections.
